CLAIM

The ornamental design for a rectangular cake plate, as shown and described.

DESCRIPTION

FIG. 1 is a front elevational view of another rectangular cake plate.

FIG. 2 is a rear elevational view of a rectangular cake plate. FIG. 3 is a left side elevational view of a rectangular cake plate.

FIG. 4 is a right side elevational view of a rectangular cake plate.

FIG. 5 is a bottom plan view of a rectangular cake plate. FIG. 6 is a top plan view of a rectangular cake plate; and, FIG. 7 is a perspective view of a rectangular cake plate. The broken lines depict portions of the cake plate that form no part of the claimed design.
